UNITED STATES PATENT OFFICE.

JOHN FRANCIS BOORAEM, OF NEW YORK, N. Y., AND BERNARD JACQUART,
OF SOUTH RIVER, NEW JERSEY.

METHOD OF MANUFACTURING TILES.

SPECIFICATION forming part of Letters Patent No. 683,635, dated October 1, 1901.

Application filed January 23, 1901. Serial No. 44,371. (No specimens.)

To all whom it may concern:

Be it known that we, JOHN FRANCIS BOORAEM, a resident of the borough of Manhattan, in the city and State of New York, and BERNARD JACQUART, a resident of South River, in the county of Middlesex and State of New Jersey, citizens of the United States, have invented a new and useful Improvement in Methods of Manufacturing Tiles, of which

10 the following is a specification.

Our invention relates to an improvement in the method of manufacturing tiles, and relates more particularly to the method of manufacturing thin straight tiles in the wet process, whereby a thin straight tile may be successfully manufactured which will be perfectly straight when completed.

In the accompanying drawings, Figure 1 represents a view in edge elevation of a 20 brick-blank from which a straight tile is formed. Fig. 2 is an end view of the same. Fig. 3 is a top plan view. Fig. 4 is a top plan view of the brick-blank after the straight tile portion has been nearly severed from the refuse portion of the blank. Fig. 5 is a transverse section taken in the plane of the line A A of Fig. 4. Fig. 6 is a top plan view of the straight tile, and Fig. 7 is a top plan view of the refuse portion of the brick-blank after it

30 has been severed from the tile.

By manufacturing thin straight tiles in the wet process there has been great difficulty in keeping the tiles straight and avoiding warping the same while being burned in the kiln.

35 To avoid this tendency to warp, it has been necessary to make the thin tile very much thicker than the requirements of the tile demanded, the tiles being used only as a facing for walls, and the thinner the facing the less space the tiles would take up in the room.

40 By means of the process to be hereinafter described we are enabled to produce a very thin straight tile which is held against warping while being burned, the refuse portion being very readily removed from the tile after it has been completed, which refuse portion may be again utilized in the manufacture of the brick-blank, and because of its having once been burned it serves to lessen the

shrinkage of the new brick-blanks to be 50 formed from the material.

We will proceed to describe our improved method of making thin straight tiles. A blank is formed of the full size of a brick by the wet process commonly used. While the 55 brick-blank is in its wet state the portion of the same which is to form the tile *a* is nearly severed from the refuse portion *b* of the blank by forming in the opposite faces of the blank two deep inwardly-extended kerfs *c d*, extending the entire length of the blank, thus leaving a long narrow web of solid material connecting the refuse portion with the tile portion. These kerfs *c d* may be formed in any desired manner and at such points as will 65 produce a tile of the required thickness. The blank is then completely dried and burned in a kiln in the usual manner, and because of the connection between the refuse portion and the tile portion the tile portion is absolutely prevented from warping, the tendency to warp being so great that the refuse portion of the blank is made very thick, so as to absolutely withstand such tendency on the part 70 of the tile to warp. After the brick-blank 75 has been completely dried and burned the refuse portion *b* may be readily broken away from the straight tile portion *a*.

The process as above described enables us to save a large amount of material in the 80 manufacture of each tile, thus serving the double purpose of producing a very thin facing-wall and also saving the cost of the additional material, which it has hitherto been necessary to utilize in the drying process for 85 giving the tile sufficient body to prevent its warping while being dried and burned.

What we claim is—

1. The herein-described method of manufacturing thin straight tiles in the wet process to prevent the warping of the tiles consisting in forming a brick-blank, then nearly severing the blank to form a thin tile portion and a thick reinforcing refuse portion connected therewith, then drying and burning 90 the blank and finally separating the thin tile portion from the thick reinforcing refuse portion of the blank, substantially as set forth.

2. The herein-described method of manufacturing thin straight tiles in the wet process to prevent their warping consisting in forming a brick-blank, then nearly severing
5 the blank by making deep kerfs in the opposite faces of the blank at such points as to form a thin tile portion and a thick reinforcing refuse portion connected by a narrow web of solid material throughout the length of
10 the blank, then drying and burning the blank and finally separating the thin tile portion from the thick reinforcing refuse portion of the blank, substantially as set forth.

Signed by JOHN FRANCIS BOORAEM at New York, N. Y., January 10, 1901.
